(57) **CLAIM**

The ornamental design for a charging apparatus, as shown and described.

DESCRIPTION

FIG. 1 is a front/right side perspective view of the charging apparatus in an open collapsed configuration.

FIG. 2 is a rear view of the charging apparatus in the open collapsed configuration.

FIG. 3 is a front view of the charging apparatus in the open collapsed configuration.

FIG. 4 is a left side view of the charging apparatus in the open collapsed configuration.

FIG. 5 is a right side view of the charging apparatus in the open collapsed configuration.

FIG. 6 is a top view of the charging apparatus in the open collapsed configuration; and,

FIG. 7 is a bottom view of the charging apparatus in the open collapsed configuration.

The broken lines merely represent portions of the charging apparatus that form no part of the claim.
